UNITED STATES PATENT OFFICE.

WALTER HENRY WELCH, OF BRISTOL, ENGLAND, ASSIGNOR TO HARVEY FROST & COMPANY, LIMITED, OF LONDON, ENGLAND.

PORTABLE VULCANIZER FOR TIRE-REPAIRS.

1,360,837.

Specification of Letters Patent. Patented Nov. 30, 1920.

Application filed March 1, 1920. Serial No. 362,175.

To all whom it may concern:

Be it known that I, WALTER HENRY WELCH, a subject of the King of England, residing at Bishopston, Bristol, in the county of Gloucester, England, have invented certain new and useful Improvements in Portable Vulcanizers for Tire-Repairs, of which the following is a specification.

10 This invention is for improvements in or relating to portable vulcanizers for tire-repairs and has for its object to provide a specific construction of vulcanizer which shall be compact in form, can be used in 15 various positions and is adapted for effecting repairs around valve-stems or in inner tubes or covers.

According to this invention a portable vulcanizer comprises a steam-generating chamber having an internal strut between the wall which provides or supports the operating face and the opposite wall, which strut is webbed to strengthen the walls, has an open way through it from the outside of 25 one wall to the outside of the other, and is shaped to receive a resilient stem constituting the holding-piece of a molding-plate, so that the said cored strut will serve the treble purpose of strengthening the generating 30 chamber; accommodating the stems of valves when effecting repairs around the same, and as securing means for molding-plates of different patterns.

In the accompanying drawings which 35 illustrate this invention:—

Figure 1 is a side elevation of the vulcanizer;

Fig. 2 is a view of the vulcanizer from the operative face;

40 Fig. 3 is a view of the same, from the base; and

Fig. 4 is a perspective view of one of the molding-plates.

The same letters indicate the same parts 45 throughout the drawings.

The vulcanizer A is of rectangular cross-section and is divided into upper and lower chambers, the upper one constituting a steam-generating chamber A¹ and the lower one a cut-out chamber A². The wall for the chamber A² may be separately attached to the bottom of the steam-generating chamber and is thus shown in the drawings; the bottom of the chamber A² is closed in by a 55 cover-plate A³.

In the interior of the steam-generating chamber is a cross-strut B which extends from the wall A³ which provides the operative face of the vulcanizer to the opposite wall A⁴ and both of these walls are 60 strengthened with webs B¹. The strut B is cored through as shown at B², the open way thus provided extending from the outer face of the wall A³ to the outer face of the wall A⁴. 65

Extending up into the generating-chamber A¹ is a tubular heating-element C which is secured to the base of the generating-chamber by a flange C¹ which is carried on the end of the tubular element and lies to 70 one side of the chamber A². Beside the flange C¹ and in the same chamber is a cut-out D. This cut-out, with the flanged heating-element, can easily be stowed in the chamber A² provided beneath the steam-generating chamber. By placing these two 75 elements side by side in the bottom of the chamber little wiring is required as the two wires C² and D³ from the heating-element (which may be bead insulated) are connected one to a terminal E¹ on the outside of a vulcanizer and the other to a terminal D² on the one contact-piece of the cut-out. 80

The terminal D¹ for other contact-piece of the cut-out is connected by a wire C³ to a 85 terminal E on the outside of the vulcanizer. It will be seen that these wires are short and are all inclosed in the chamber A² so that there is little to get out of order and the assemblage of the parts can be quickly 90 effected, which means that the apparatus can be cheaply made.

On the outside of the vulcanizer and on one side wall of the same, a water-gage glass F is secured. This is provided with a 95 central mark indicated at F¹ and by being placed obliquely it will indicate whether the vulcanizer contains sufficient water irrespective of the position in which the vulcanizer may be used, as the capacity of the 100 steam-generating chamber is such that if it contains the proper quantity of water, it will always register approximately on the mark F¹. It will be seen that the mark is not a mere line and allows for slight variations such as may occur when the vulcanizer is used in different positions. 105

The object of the webbed strut B, B¹, is to strengthen the walls A³ A⁴ so that a cramp may be applied to the wall A⁴ to 110

press the wall A^3 against the work to be vulcanized. The throughway B is of such dimensions as to accommodate a valve stem when repairs are being made around the 5 same so that the inner tube can be brought into close contact with the face A^3 and it is also of such shape, in this case circular in cross-section, that it can receive the holding-piece of a molding-plate.

10 In Fig. 4, a molding-plate G is shown, one surface G^1 of which is flat to lie flush against the face A^3 and the opposite surface G^2 is curved to fit the curvature of a tire-cover and patterned to conform with the 15 outer configuration of the tire. Secured to the back of this plate is a tubular holder G^3 which is slotted with V-shaped slots to render it resilient, and this is made a spring fit in the throughway B^2 of the internal 20 strut B . Any molding-plate can thus be readily placed in position by pushing its holding-piece G^3 into the hole B^2 and the curved face of the molding-plate then becomes the operative surface of the vulcanizer.

25 The vulcanizer constructed as described is easy to manufacture, is compact, serves a large number of purposes, and can be used in various positions without fear of the 30 heating-element not being immersed provided the water-level is maintained at the mark shown on the gage.

The flat form of cut-out shown in the drawings furthers the compactness of the 35 apparatus as by this means little depth is required by the chamber A^2 and its arrangement close beside the end of the heating-element C, C^1 , reduces the wiring to a minimum.

40 It will be seen that the stem G^3 of the molding-plate is held frictionally in the orifice B^2 , and obviously other devices can be employed instead of this which will also be frictionally engaged in the said orifices, for 45 example, the stem may be in the form of a plain tube fitting snugly in the orifice and it may be provided with two spring-controlled balls projecting laterally from the tube which engage an internal circumferential channel in the cored orifice B^2 so that 50 when the stem is pushed in, the balls snap into the channel in the well-known manner and will thus frictionally engage the stem with the vulcanizer. Whatever frictional 55 device is employed, the orifice B^2 must be so shaped and dimensioned as to give the required grip without positively locking the stem in the orifice.

What I claim as my invention and desire 60 to secure as Letters Patent is:—

1. In a portable vulcanizer, the combination of a chamber having an outer heating face on one wall thereof and containing a strut arranged between said face and the 65 opposite wall, which strut is webbed to

strengthen said walls and has a thoroughway extending from said face to the outside of the said opposite wall, and means for generating steam in said chamber, for the purpose described. 70

2. In a portable vulcanizer, the combination of a chamber having an outer heating face on one wall thereof and containing a strut arranged between said face and the opposite wall, which strut is webbed to 75 strengthen said walls and has a thoroughway extending from said face to the outside of the said opposite wall, a molding plate having a stem adapted to be frictionally held in said throughway, and means for generating steam in said chamber, for the purpose described.

3. In a portable vulcanizer, the combination of a casing having a partition dividing the same into a steam-generating chamber 85 and a cut-out chamber, said steam-generating chamber having an outer heating face on one wall thereof and containing a strut arranged between said face and the opposite wall, which strut is webbed to strengthen 90 said walls and has a thoroughway extending from said face to the outside of the said opposite wall, a heating element having a flanged base mounted on said partition in said cut-out chamber and extending into 95 said steam-generating chamber, and a cut-out device of flat form mounted on said partition and operatively connected with said heating element, substantially as and for the purpose described. 100

4. In a portable vulcanizer, the combination of a chamber of rectangular cross-section having an outer operative heating face on the front wall thereof and containing a strut arranged between the front and rear 105 walls, which strut is webbed to strengthen said walls and has a thoroughway extending from said face to the outside of the rear wall, a water-gage mounted diagonally on one side wall of the chamber and having its 110 ends opening into the same, one end relatively near to the said front wall and the other relatively near to the said rear wall, at opposite sides of said strut, and means for generating steam in said chamber, for 115 the purpose described.

5. In a portable vulcanizer, the combination of a casing of rectangular cross-section having a partition dividing the same into a larger steam-generating chamber and a 120 smaller cut-out chamber, said steam-generating chamber having an outer operative heating face on the front wall thereof and containing a strut arranged between said face and the rear wall of the casing, which 125 strut is webbed to strengthen said walls and has a thoroughway extending through said steam-generating chamber, a diagonally-disposed water-gage mounted on one side wall of the casing and opening into the steam- 130

generating chamber at opposite sides of said strut, a heating-element having a flanged base mounted on said partition in said cut-out chamber and extending into said steam-
5 generating chamber, a cut-out device mounted on said partition and operatively connected with said heating-element, and a

molding plate having a stem adapted to be frictionally held in said throughway with the rear of the plate abutting against said 10 heating face, substantially as and for the purpose described.

In testimony whereof I affix my signature.

WALTER HENRY WELCH.
